(57) **CLAIM**

I claim the ornamental design for food utensils, as shown and described.

DESCRIPTION

FIG. 1 is a perspective view of a food utensil, showing my new design;

FIG. 2 is a top view thereof;

FIG. 3 is a right side view thereof, the left side being a mirror image thereof;

FIG. 4 is a bottom view thereof;

FIG. 5 is an enlarged cross sectional view taken along line 5-5 of FIG. 1, for better illustrating the surface contours thereof

FIG. 6 is a rear view thereof;

FIG. 7 is a perspective view of another food utensil, showing my new design;

FIG. 8 is a top view thereof;

FIG. 9 is a right side view thereof, the left side being a mirror image thereof;

FIG. 10 is a bottom view thereof;

FIG. 11 is an enlarged cross sectional view taken along line 11-11 of FIG. 7, for better illustrating the surface contours thereof;

FIG. 12 is a rear view thereof;

FIG. 13 is a perspective view of yet another food utensil, showing my new design;

FIG. 14 is a top view thereof;

FIG. 15 is a right side view thereof, the left side being a mirror image thereof;

FIG. 16 is a bottom view thereof;

FIG. 17 is an enlarged cross sectional view taken along line 17-17 of FIG. 13, for better illustrating the surface contours thereof; and,

FIG. 18 is a rear view thereof.

The broken lines shown in the drawings form no part of the claimed design.

1 Claim, 6 Drawing Sheets
